UNITED STATES PATENT OFFICE

GEORGE KNOWLES, OF OTTAWA, ONTARIO, CANADA

PROCESS OF CLEANING VEGETABLE FIBER AND THE LIKE

Application filed February 6, 1928. Serial No. 252,372.

This invention relates to improvements in a "process of cleaning vegetable fiber and the like" and appertains particularly to a new and more efficient way of separating the 5 woody or pulpy parts from the fiber, without damaging the latter, so that the fiber is thoroughly cleaned of all trace of shives, hurds, or other woody pith or bark or other vegetable matter intended for discard, and emerges in 10 a satisfactory condition, cleaned, worked and polished.

An object of the invention is to provide a process to effect the desired result in the treatment of flax, hemp and similar fibers, 15 comprising breaking the woody body into short fragments, scraping these out of the stock from among the fiber then working, shaking and polishing the fibers.

A further object of the invention is to provide 20 a process as described and means for effecting the same wherein the fiber bearing stock is fed to a series of interworking fluted intake and crushing rollers that break the woody body without causing damage to the 25 fiber; passed over a table and at the end thereof, subjected to the action of a fast revolving scraper with only sufficient clearance from the table to safeguard the fiber and that beats the fiber down off the edge thereof and 30 throws the shives, hurds or other chips onto a discharge chute; polished between a covered roller and the depending skirt from the table; and finally shaken and worked, in a way that adds to the polish, between a pair of revolving 35 closely intermeshing slats before being deposited on the delivery conveyor.

A still further object is the provision of the process and means for effecting the same 40 as described that is rapid, simple and thorough; easily set up and maintained; capable of operation at a reasonable cost; and in all highly desirable from the standpoint of cost and efficiency.

To the accomplishment of these and related 45 objects as shall become apparent as the description proceeds, my invention resides in the essentials of the process, and the construction, combination and arrangement of parts in the means of effecting the same as shall be 50 hereinafter more fully described, illustrated

in the accompanying drawings and pointed out in the claims hereunto appended.

The invention will be best understood and can be most clearly described when reference is had to the drawings, forming a part 55 of this disclosure wherein like characters indicate like parts throughout the several views.

In the drawings:—

Figure 1 is a side elevation of a machine 60 for carrying out my improved process;

Figure 2 is a similar elevation of the reverse side of the machine;

Figure 3 is a vertical section taken as looking 65 from the same side as Figure 1; and

Figure 4 is a fragmentary detail view of a slightly modified form of the invention.

As, in an explanation of the machine that is illustrated and the operation thereof, the process of cleaning the fiber will become apparent and be fully and clearly set forth, no introductory description of the process itself will be made. 70

This fiber cleaning and polishing machine 75 comprises essentially a frame work composed of a pair of upright parallel ends 7 spaced at the bottom by the bars 8. Near the top of the frame, a feed table 9 enters the machine at the front and is supported on the bracket 10. Vertical pairs of intermeshing 80 fluted steel rollers 11 extend rearwardly in a horizontal line from this feed table, the lower rollers being carried on the shaft ends 12 journaled in the frame ends 7 while the shaft ends 13 of the upper rollers, in each 85 pair, are vertically adjustable in the slots 14 in the frame ends 7, by means of the adjusting screws 15, threaded vertically in the frame ends, and swivelled to the intermediate cushion bearing blocks 16 on which they 90 work.

At one end, the shaft ends 13 of the upper rollers 11 carry keyed gear pinions 17 that mesh with a large gear wheel 18 mounted on the frame end 7 having an integral chain 95 sprocket wheel 19 driven by the chain 20 from the sprocket gear 21 on the drive shaft 22. This shaft extends the length of the machine running in bearings in the ends 7 and at the end remote from the sprocket 21 car- 100

ries a fly wheel 23 and a second sprocket 24 for a purpose to be later explained; the shaft 22 being driven from any suitable power source.

5 Behind the pairs of fluted rollers is a short sloping table 25 that terminally depends in a vertical skirt 26 and working above this table is the scraper 27. This scraper is here shown as a roller with radial blades 28. The 10 roller is normally centered on a line at right angles with the lower or rear end of the table and is adjustable with relation to the table 25 by means of the bearings 29 in which its spindle ends are carried, said bearings 29 in- 15 cluding slots 31 through which bolts 32 extend in fastening them to the supporting frame ends 7. A sprocket wheel 33 is keyed exterior of the frame to the spindle end 20, at the side of the machine remote from the 20 sprockets 19 and 21 and the chain 20.

A rubber coated roller 34 is positioned close up under the scraper 27 and closely spaced from the skirt 26 of the table 25. The spindle ends 35 of this roller are likewise 25 supported in the frame ends and one is provided with a keyed sprocket wheel 36, on the same side as the sprocket 33.

Beneath the roller 34 is a pair of interworking slats 37 that are connected at one 30 end by the intermeshing timing gears 38 while at both ends both slats have bearing spindles 39 suitably supported by the frame ends 7. One of these spindles 39 of the forward slat extends through the frame end 7 35 and carries a keyed sprocket wheel 40 at the same side as the sprockets 24, 33 and 36. A drive chain 41 runs around the sprockets 24, 33 and 36 and returning passes across the top of the sprocket 40 and thence under an 40 idler 42 on a tightening arm 43. It will be noted that the sprockets 33, 36 and 40 are 45 small compared with the sprocket 24, while the sprockets 19 and 21 are the same size, consequently though the sprocket 19 drives the fluted rollers through the medium of the gear 18 and pinions 17; the scraper 27, rubber coated roller 34 and the beating slats 37, 50 all of lesser dimensions than the large fluted rollers, are working more rapidly.

50 From a point between the scraper 27 and the rubber coated roller 34 at the back of the machine, a discharge chute 44, is extended from the frame and supported by the transverse bracket 45. Running out rearwardly 55 from the frame and from beneath the working slats 37, is a travelling delivery conveyor 46 for the cleaned fiber.

Following such a minute description of the 60 various parts of this machine it should here suffice in conclusion to make but brief reference to its use and modus operandi and thereby to indicate very clearly its purpose and the fiber cleaning process it makes possible: As 65 fiber bearing stock, taking hemp for instance,

is fed along the table 9 to the fluted rollers 11 turning in the direction of the arrows, it is caught between the teeth thereof and drawn in and advanced therethrough being treated by these pairs of rollers to the extent of having all the woody body broken into small fragments that, as the stock continues on over the table and under the fast revolving scraper, is thrown out onto the discharge chute, the fiber stands clinging close to the skirt of the table due to the beating action of the scraper and thence down between the table skirt and the fast rolling rubber coated drum.

70 It may now be particularly pointed out that the cleaning of the fiber depends largely on its treatment under the scraper for here the fiber must be carefully protected yet the hurds are to be entirely removed. The locating of the scraper axis on a line projected at 75 right angles from the rear or lower side of the table proper is most important for its affords the scraper blades the best opportunity of thoroughly cleaning the fiber of the dischargeable wood content, beats the fiber 80 down against the skirt and prevents injury to the fiber at this point; thus it becomes obvious that the accurate setting of the scraper 85 in relation to the table is essential. As the fiber passes between the rubber coated roller and the table skirt, being pressed against the 90 said skirt and thus snugly retained between the roller and skirt, the rate at which the roller is rotated, as in the case of the scraper, 95 is greater than the speed of travel of the fiber so that the same is highly polished here and passing to the interworking slats or beaters 100 is further worked and shaken and polished, issuing onto the endless conveyor belt in a 105 finely cleaned and polished condition.

110 From the foregoing description taken in connection with the accompanying drawings, it will be manifest that a process of cleaning vegetable fiber and the like is provided that will fulfil all the necessary requirements of such a device but as many changes could be made in the above description and many apparently widely different embodiments of my invention constructed within the scope of the 115 appended claims without departing from the spirit or scope thereof, it is intended that all matters contained in the said accompanying specification and drawings shall be interpreted as illustrative and not in a limited sense.

120 Having thus described my invention, what I claim as new and desire to secure by Letters Patent is:—

125 1: A process for cleaning vegetable fiber and the like comprising cutting and breaking the stock; passing the pressed and broken fibers over a table; scraping out the woody fragments from the fibers as they start across the table and discharging said fibers onto a 130

discharge table; and holding said fibers against said table after separation therefrom of the woody fragments; and shaking and cleaning of said fibers as they are held against 5 said table.

2. A process for cleaning vegetable fiber and the like comprising crushing and breaking vegetable fiber and passing the same over the face of a table; scraping out the woody 10 fragments and discharging the same onto a discharge table; pressing said fibers against the face of the table past the point at which the woody fragments are scraped out from among the fibers; and shaking and cleaning 15 said fibers at a further point while the fibers are still pressed against the table.

3. A process and apparatus for cleaning vegetable fiber and the like comprising crushing and breaking means through which the 20 plant stalks are passed from a feeding table and then over a second table after passing through the crushing and breaking means; a scraping means working against one face of the second table to separate from the fiber 25 woody fragments crushed and broken therefrom; the woody fragments being discharged onto a discharge table opposite said second mentioned table; the remaining fibers being pressed against the second mentioned table 30 after separation therefrom of the fragments; said fibers being polished as they are pressed against the second mentioned table; and finally scraping and cleaning said fibers as 35 they leave said second mentioned table and while they are still pressed against said second mentioned table.

In testimony whereof I hereunto affix my signature.

GEORGE KNOWLES.
